UNITED STATES PATENT OFFICE.

FRANK M. BROOKS, OF NEW YORK, N. Y.

LIGHTING-FIXTURE.

1,155,789.

Specification of Letters Patent.

Patented Oct. 5, 1915.

Application filed November 30, 1914. Serial No. 874,656.

To all whom it may concern:

Be it known that I, FRANK M. BROOKS, a citizen of the United States, residing in the borough of Brooklyn, in the county of Kings, city and State of New York, have invented an Improvement in Lighting-Fixtures, of which the following is a specification.

My present invention relates to lighting fixtures and more particularly to the parts forming the clamping or gripping member, by which the bowl or globe is secured in position in the fixture.

Heretofore, in lighting fixtures, the bowl or globe has been supported and maintained in position in various manners by devices making a substantially unyielding gripping engagement or connection with the rim of the bowl or globe. For example, in some instances, the rim of the bowl or globe has been set within a ring, and set screws have been employed to maintain the bowl or globe in position. In other cases, the supporting member or clamp has been provided with a pin adapted to pass through an aperture provided therefor in the rim of the bowl or globe, which pin, within the bowl, is provided with a nut, or other similar device, adapted to be turned down against the inner surface of the rim to secure the parts in place. In these, and all similar constructions, the connection between the hanger or support in the bowl or globe is, as hereinbefore stated, substantially unyielding, and consequently the parts have to be adjusted to position with much care, in order to allow for the expansion and contraction of the bowl or globe, due to the different temperatures to which it is subjected. I am also aware that in lighting fixtures, there have been employed clamp members provided with yielding devices to engage the inner surface of the rim of the bowl, as for example, as shown and described in Letters Patent No. 1,115,166, granted to me October 27, 1914, for a lighting fixture hook. Even in the use of these yieldingly engaging hooks, however, some care is also necessary in adjusting the parts to position, and furthermore, when placed, the yielding member is in direct contact with the surface of the bowl, as is the case with the clamps which are entirely unyielding in their nature. Furthermore, in all such cases, it is necessary to adjust the parts to position after the bowl or globe is set in place in the fixture.

Now the object of my present invention is the provision, in a lighting fixture, of a connection between the hanger and the support of the bowl, which is yielding in its nature, and the parts of which may be assembled in their permanent positions before the globe is set in place, the parts being so constructed that the engaging members of the fixture are yielding and may be applied to the bowl so that, when in place, these yielding parts return to their normal positions and retain the bowl and globe in position, as will be hereinafter more particularly described.

In the drawing, Figure 1 is an elevation and partial section of a lighting fixture embodying my present invention. Fig. 2 is a sectional plan of the same. Fig. 3 is an enlarged perspective view illustrating one of the clamp or gripping members. Fig. 4 is an elevation showing the inner side of one of the clamp members, and Fig. 5 is an elevation and partial section of the end of one of the hanger rods or support arms.

Referring more particularly to the drawing, in carrying out my invention, I employ a base or socket member 10, to which are suitably connected depending arms or hangers 11. It will be understood, however, that while I have illustrated a ceiling fixture, the invention hereinafter described is equally applicable to side wall, or other fixtures, and also, while I have illustrated the depending members or support arms 11 as tubular, that a chain or other similar means, which are sometimes employed, may be used without departing from the nature and spirit of my invention.

At the lower extremity of each depending member 11 is an end member 12. On one side, each end member 12 is provided with a lug 13, and at its diametrically opposite side with a lug 14. The lug 13 is preferably rectangular in cross section, and centrally is provided with a tapped recess 15. The lug 14 may be of any configuration in cross section, and adjacent its extremity is provided with a tapped aperture 16. A clamp or gripping member, adapted to engage the outer surface of the rim of the bowl, is indicated at 17. This is provided, in a suitable position, with a boss 18, notched as indicated at 19, to fit over the lug 13, and also apertured at 20, in order that the screw 21 may be passed through the boss 18 and turned down into the tapped opening in the

lug 13 to secure the clamp 17 in position relatively to the lug. As will be understood, the clamp member 17 may be of any suitable design, providing portions thereof are 5 adapted to engage the concave or other outer surface of the rim 22, of the bowl or globe 23, as is clearly illustrated in Figs. 2 and 3 of the drawing. I also employ a ring 24, made of suitable resilient material, and 10 adapted in spaced positions, depending upon the number of hangers employed, to be secured to the lugs 14 by means of screws 25 passing through apertures provided therefor in the ring and turned down into 15 the tapped apertures 16 adjacent the extremities of the lugs 14. Also, as is clearly indicated in the drawing, the lugs 13 and 14 are so positioned that when in place the ring 24 will normally assume a position 20 spaced an appreciable distance from the inner surface of the rim 22 of the bowl 23.

As indicated in Fig. 2, a gas burner 26 may be employed in the lighting fixture, in which instance one of the depending members 11 is utilized as a gas pipe, but, as will 25 be understood, a suitable electric light fitting may also be used instead of the gas burner as illustrated.

In setting the bowl in position, in the fixture hereinbefore described, the rim of the bowl is placed in position between two of the clamps in the adjacent portions of the ring 24, whereupon the third clamp and its 30 depending member may be sprung sufficiently far, relatively to the other depending members, to permit the clamp associated with the third depending member to be placed in position on the outer surface of the rim of the bowl, and in so doing, the 35 ring member 24 will also be sprung from its normal position to substantially that shown in dotted lines in Fig. 2, and upon releasing the third depending member and its clamp, or the one that has been slipped over the 40 edge of the bowl, the resilient ring 24 will return to its normal position, also returning the depending members or hangers to their 45 normal positions and causing the clamp members to engage the outer surface of the 50 rim of the bowl with sufficient force to maintain the same in position in the fixture.

In the drawing, I have illustrated a fixture in which there are three depending or support arms, but, as will be apparent, two, 55 four, or more, may be equally well employed. Also, as hereinbefore stated, this structure provides a fixture in which the parts may be assembled and set in place permanently before the globe is put into position, and in which no adjustment of the 60 parts is necessary in setting the globe in place.

I claim as my invention—

1. In a lighting fixture, a plurality of supports, a globe engaging member fixed at 65 the extremity of each support and a resilient member extending between the said supports and connected to each globe engaging member and adapted to lie within a globe in a position spaced apart from the same, 70 and also from the said globe engaging members.

2. In a lighting fixture, a base, a plurality of members depending therefrom, a globe 75 engaging member secured at the extremity of each of the said depending members, and a resilient member extending between and connecting each of the said depending members in a position spaced apart from the said globe engaging members.

3. In a lighting fixture, a base, a plurality of depending support arms connected thereto, lugs extending in diametrically opposite positions from the extremities of the said depending support arms, a globe engaging 85 device connected to the corresponding lugs of each of the said depending support arms, and a resilient ring connected to the other and corresponding lugs on each of the said depending support arms in a position spaced 90 apart from the said globe engaging devices.

4. In a lighting fixture, a base, a plurality of depending support arms connected thereto, end members fixed at the extremities of each of the depending support arms, a lug 95 extending outwardly from each of the said end members, a lug extending inwardly from each of the said end members, a globe engaging device for each of the said end members, means for securing the same 100 thereto, and a resilient device extending between and connected to the said inwardly extending lugs in a position spaced from the said globe engaging members.

5. In a lighting fixture, a base, a plurality of depending support arms secured thereto, an end member fixed at the extremity of each of the said support arms, a lug extending outwardly from each end member, a lug extending inwardly from each end member, 110 a globe engaging member secured to the outwardly extending lug to each of the said end members, and a resilient ring secured to each of the said inwardly extending lugs of the said end members so as to assume a position normally spaced from the rim of a globe when in contact with the said globe 115 engaging members.

Signed by me this 25th day of November, 1914.

FRANK M. BROOKS.
